Primary Examiner — Ramzi S Almatrahi(74) *Attorney, Agent, or Firm* — Anova Law Group,
PLLC(57) **CLAIM**The ornamental design for a camera, as shown and
described.**DESCRIPTION**FIG. 1 is a front perspective view of a camera showing my
new design;

FIG. 2 is a back elevation view thereof;

FIG. 3 is a front elevation view thereof;

FIG. 4 is a top plan view thereof;

FIG. 5 is a right side elevation view thereof;

FIG. 6 is a left side elevation view thereof; and,

FIG. 7 is a bottom plan view thereof.

The broken lines depict portions of the camera in which
the design is embodied that form no part of the claimed design.**1 Claim, 7 Drawing Sheets**(56)
